DESIGN FOR A WORKBENCH

Edward Ralph Harris, Evanston, and Arthur Fuller Dean, Barrington, Ill., assignors to Stewart-Warner Corporation, Chicago, Ill., a corporation of Virginia

Application March 15, 1941, Serial No. 99,635

Term of patent 7 years

To all whom it may concern:

Be it known that we, Edward Ralph Harris and Arthur Fuller Dean, citizens of the United States, residing, respectively, at Evanston and at Barrington, in the county of Cook and State of Illinois, have invented a new, original, and ornamental Design for a Workbench, of which the following is a specification, reference being had to the accompanying drawing, forming part thereof.

Fig. 1 is a front perspective view of the workbench, showing our design; and

Fig. 2 is a side elevational view thereof.

We claim:

The ornamental design for a workbench, as shown.

EDWARD RALPH HARRIS.
ARTHUR FULLER DEAN.
